YARN SEVERING MECHANISM FOR WRAP STRIPE MACHINES

Augustin Gagne, Central Falls, R. I., assignor to
Hemphill Company, Central Falls, R. I., a cor-
poration of Massachusetts

Continuation of application Serial No. 379,302,
July 18, 1929. This application October 27,
1932, Serial No. 639,918. Renewed October 14,
1937

13 Claims. (Cl. 66—134)

This invention relates to a mechanism for severing partial course yarns, such as the high splice and double sole yarns, when such yarn is knitted into the fabric for partial courses in combination with the knitting of wrap stripes in a manner identical with or similar to that disclosed in the patent to Lawson 1,702,608, February 19, 1929. This application is a continuation of application Ser. No. 379,302, filed July 18, 1929. Furthermore, this invention is directed to a 10 specific embodiment of the invention broadly described and claimed in the patent to Lawson 1,842,974, January 26, 1932.

In the drawings:

Fig. 1 is a view in plan showing the so-called 15 latch ring of a knitting machine, associated with which latch ring are main and auxiliary yarn severing mechanisms as well as a means for wrapping threads around selected or other needles;

Fig. 1a is a detail view;

Fig. 2 is a sectional view taken along the line 20 2—2, Fig. 1, showing also a portion of the needle cylinder in section;

Fig. 3 is a fragmentary view partly in section, taken along the line 3, Fig. 2, of the latch ring 25 shown in Fig. 1, certain of the parts being removed more clearly to show the operation of the main and auxiliary yarn severing mechanisms;

Fig. 4 is a fragmentary detail view of a portion of the latch ring.

Fig. 5 is a fragmentary view in elevation and partly in section of the clamping and cutting mechanisms for the main yarns;

Fig. 6 is a fragmentary elevational view partly in section showing an auxiliary yarn severing mechanism;

Fig. 7 is a detail view of a clamp which operates temporarily to retain yarns; and

Figs. 8-12 inclusive are more or less diagrammatic views showing successive positions of wrap threads and a partial-course or reinforcing yarn.

The latch ring indicated generally by the numeral 1 is provided with the usual extension carrying a series of thread or yarn levers 2, 3, 4, 5 and 6 all of which are pivotally mounted upon a pivot pin 7 itself supported in bearings provided by ears or lugs 8 attached to and extending upwardly from the said extension of the latch ring. The needles which are indicated generally by the numeral 9 are slidably mounted in slots provided in the needle cylinder 9' such needles being controlled in their movements by cams not shown. The needle cylinder 9' is driven to rotate in the direction of the arrow, Fig. 1 to 55

pass the usual mouthpiece 10 within which the mentioned yarn levers are seated when in their feeding positions. The body of the stocking or other fabric may be knitted with one or more 5 main yarns 11 as well as a partial-course yarn 12, such yarn being shown as fed through an eye provided in the yarn lever 2. The said yarn 12 is or may be what is ordinarily called the high splice yarn and is fed to one-half, more or less, of the needles during the knitting of the high splice and/or double sole portion of a stocking. As this invention is primarily concerned with the knitting of the yarn 12 and wrap threads such as 13 or 13', the following description will be confined to yarn 12 and threads 13, 13'.

It will be understood that the yarn 12 is referred to as a "yarn" and the threads 13, 13' are each referred to as a "thread" merely for the purpose of avoiding confusion in the following description, the terms "yarns" and "threads" being interchangeable.

The threads 13, 13' pass through eyes 14, 14' in a disc 15 which corresponds in function to the disc 117 disclosed in the Lawson patent 1,702,608, and although two threads 13, 13' have been shown, any number of such threads may be utilized.

Situated about 90 degrees in advance of the mouthpiece 10 the latch ring 1 is provided with a lateral extension or arm 16 which is pivotally connected to the frame of a knitting machine in the usual manner, thereby permitting the latch ring to be elevated to a position above the needles whenever desirable. Attached to the extension 16 as by means of screws 17 is a bracket plate 18 which projects more or less radially above and across the needle circle to a position inside thereof where it terminates in a split collar 19 the ends whereof embrace a rod 20 such rod being held against movement therein as by means of a set screw 21. Surrounding the rod 20 is a coil spring 22 one end 23 of which is in engagement with the upper edge or surface of an automatically actuated clamp 24 which is pivoted intermediate its ends as at 25 to a block 26. The rod 20 and block 26 are secured together in any suitable manner and connected thereto is a so-called binder plate 27 more or less circular in outline and provided with a recess or opening 27'. The upper portion of the spring 22 bears against the collar 28 which is secured to rod 20. At the other side of the block 26 (Fig. 5) there is pivotally connected at 29 a movable blade 30 of a cutter, the cutting edge of which is adapted to cooperate with the fixed cutting blade 31

which is rigidly fastened to the block 26 in any suitable manner. A spring 32 which is fastened to the blade 30 by the screw 29 normally maintains the blades 30 and 31 in a shearing relationship. Plate 27 is provided with an opening or recess 33 thereby permitting the blade 30 to move to the position shown in Fig. 5 so that a withdrawn yarn may be received between the two cutting blades 30 and 31. Positioned between clamp 24 and the cutter 31 is a non-automatically controlled clamp 34 which serves lightly to clamp the yarns while the automatically actuated clamp 24 and movable cutting blade 36 are in the position shown in Fig. 5. The clamp 34 is pivoted to block 26 which is slotted as at 35 within which slot the inner end of the clamp 34 is received and through which slot and hole 36 in clamp 34 the pin 37 passes.

The clamp 24 and movable cutting blade 30 are automatically actuated at predetermined times by means of automatically actuated connections, connected to and leading from a lever 38 which is pivoted intermediate its ends as at 39 to a lug 40 upstanding from and connected to the bracket plate 18. The inner arm of the lever 38 has pivotally connected thereto at 41 (Fig. 5) a depending link 42 intermediate the ends of which is rigidly connected as by means of screws 43 an arm 44, a turned end of which terminates in a downwardly extending lug 45 which engages an arm of the yarn clamp lever 24. When the lever 38 is automatically actuated to move the link 42 downwardly, the lug 45 rocks the clamp 24 thereby causing the same to assume the position shown in Fig. 5. At the same time the movable cutting blade 30 is moved to the open position shown in Fig. 5 due to the lower portion of the link 42 being pivotally connected at 46 to the said blade 30. Movement of the lever 38 in the opposite direction is caused by means of the spring (not shown) common to Banner ma-

chines. Fastened to the upper face of the latch ring 1 is an elongated bracket 47 and upwardly projecting from the ends thereof are bearing lugs 48, 49 through which a shaft 50 passes. Secured to the shaft 50 adjacent to the outer faces of the lugs 48 and 49 are collars 51 and 52 which are secured in adjusted position by means of set screws 53 and 54. Thus the collars prevent endwise movements of the shaft 50 with respect to the bracket 47. The end of the shaft 50 projecting beyond the collar 52 has connected thereto as by means of an adjusting screw 55 a lever arm 56. Fastened to the underside of the lever arm 56 is a plate 57 the lower face of which is normally in contact with the upper face of the yarn lever 2 intermediate the ends of the latter. The plate 57 is provided with a hole through which passes a screw or stud 58 around the shank of which is a coil spring 59 which yieldingly maintains the forward end of the plate 57 in contact with an adjustable stop 60 which passes through the free end of the arm 56. Thus it will be seen that the screw 55 provides a means for adjustably positioning the lever arm 56 with respect to the yarn lever 2, and the plate 57, and that the adjusting means therefor just described, provide an adjustment for the said arm 56 supplemental to the aforesaid adjustment provided by the screw 55. The other end of the shaft 50 terminates in a turned end 61 which (Fig. 6) engages under a pin 62 laterally extending from a slid able rod 63 which terminates at one end in a movable blade 64 of an auxiliary cutter. Blade 64 is nor-

mally spaced from a fixed blade 65 as shown in Fig. 6. The rod 63 is provided with longitudinal slots 66 passing through which are pins or screws 67 which are fastened to a bracket 68. Also secured to the bracket 68 is the fixed element 65 of the cutter.

As will be evident, when the high splice or other partial-course lever 2 is elevated to an inoperative position, such elevation raises the adjacent end of the lever arm 56 thereby rocking the shaft 50 and consequently the other arm 61 of the lever which in turn acts upon the pin 62 and causes movement of the blade 64 to the position shown in Fig. 6. With the parts in such position the last needle knitting the high splice or other partial-course yarn 12, carries such yarn around the needle circle in the direction of the arrow, Figs. 1 and 3, to the position indicated at 69, Fig. 3, at which time the thread 12 is between the blades 64 and 65 as indicated in Fig. 6. Thereupon, the yarn lever 2 is dropped to the feeding position as indicated in Fig. 3 whereupon the lever arm 56 is permitted to drop thereby rocking the lever arm 61 to a relatively lowered position, the movable blade 64 then severing the yarn 12, leaving a severed yarn end 69'. Movement of the blade 64 and arm 61 to a relatively lowered position is caused by means of a spring 10 which is coiled around a pin or screw 11 the end of which passes through a plate 72, one end of which is provided with a hole through which passes the rod 20 and into a bracket arm 73. The plate 72 which constitutes a lever rests upon the upper face of bracket arm 73 which is made fast to the rod 20 as by means of a set screw 74. The other end of the bracket arm 73 has affixed thereto and depending therefrom the before mentioned bracket 68. The free end of the lever 72 terminates in a reduced end 15 which is received within a notch 76 in the upper edge or surface of the slid able rod 63, the result being that the spring 10 urges the reduced end 15 downwardly thereby causing the movable blade 64 and lever arm 61 to move to a relatively lowered position as compared with that shown in Fig. 6, thus severing yarn 12.

In Fig. 1 the wrap stripe disc 15, which is shown as overlapping the needle circle and being received within a recess 11 provided in the latch ring 1, is preferably driven to rotate in timed relation, such as one and one, with the needles 9 and needle cylinder 9' in a manner similar to or identical to that disclosed in the Lawson Patent 1,702,608.

By referring to Figs. 8-12 inclusive, wherein is disclosed successive positions of the yarn 12 and wrap thread 13, the necessity for acting upon the yarn 12, such as by means of severing the same at least once during the knitting of each course, will be apparent.

In Fig. 8 the lever 2 is shown as just having been elevated to an inoperative position at which time the thread 13 is shown as being well within the needle circle, both the needles 9 and the disc 15 moving in the direction of the two arrows. Continued rotation of the needles finally brings the last needle knitting the thread 12, and indicated by the numeral 78, to the position shown in Fig. 9 in which position the thread has been received between the blades 64 and 65 as indicated in Fig. 6, the threads 13 and 13' having moved to the relative circumferential positions shown in said Fig. 9. At about this point in the knitting cycle the movable blade 64 is automatically actuated in the manner hereinbefore described so as to sever

the yarn 12 closely adjacent to the needle 78. Severance of such yarn permits the thread 13 to move to the relative circumferential position shown in Fig. 10—the usual thread take-up shortening the float leading from the last needle 79, wrapped during the preceding course of knitting, to the eye 14 in the disc 15—the thread 13 passing from the needle 79 around a semi-circular finger 80 and up to and through eye 14. Continued rotation of the needles and disc 15 finally brings the float of the thread 13 to the position shown in Fig. 11 and then to the position shown in Fig. 12 where the bight of thread which passed around the finger 80 passes off such finger, the mentioned thread take-up then causing the mentioned bight of thread 13 to lie closely adjacent to the inner face of the fabric. As the needles and disc 15 move from the position shown in Fig. 10 to the position shown in Fig. 11 the thread 13 is wrapped around selected needles, which may be the same needles wrapped during the preceding course of knitting, after which the cycle of operations hereinbefore described is repeated.

If the auxiliary cutter or some equivalent means had not been provided, the yarn 12, which is shown in Fig. 9 as leading from the yarn guide 2 to the needle 78, would upon continued rotation of the needles and disc 15 draw out or unduly elongate the float of thread 13 passing from the needle 79 to the eye 14, this being due to the fact that the float of thread 13 (Fig. 9) passes under the yarn 12 and then to a position above the same through the eye 14.

As will be apparent from inspection of Figs. 9, 10 and 11, the non-automatically actuated clamp 34 serves to clamp the yarn 12 and retain it in position above the needles after the yarn guide 2 has been elevated to the position shown in Fig. 9, and until the said yarn is again knitted into the fabric by the leading needle knitting the high splice or other partial-course yarn. Fig. 10 shows the yarn guide 2 as having been restored to an operative position, the yarn 12 having been knitted by a few of the leading high splice or other needles.

Continued rotation of the needles from the position shown in Fig. 10 to that shown in Fig. 11 causes the float of the yarn 12 to be carried around a pin 81, whereupon such pin 81, acting in conjunction with the rotating needles, pulls the float of the yarn 12 in a direction transverse or at right angles to the clamp 34.

The clamp 34 performs two functions, serving to act as a clamp in conjunction with the auxiliary cutting mechanism and also serving as an auxiliary or temporary clamp for the main yarns when the main clamp 24 is in the position shown in Fig. 5.

It will be understood that during high splice or other partial course knitting, the floats of the yarn 12 pass between the forks constituting the clamp 24, the floats of the yarn 12 not passing underneath the clamp 24 except when the said yarn 12 is withdrawn at the completion of partial-course knitting.

The main clamping and cutting mechanism, comprising the clamp 24 and cutter 30, 31, is not adapted to sever the yarn 12 during the knitting of partial courses, although it is adapted to sever such yarn as well as any of the other main yarns when they are withdrawn from feeding relation with respect to the needles after the knitting of complete courses. Furthermore, the auxiliary cutting mechanism 64, 65 serves to sever the yarn

12 during the knitting of partial courses only, such auxiliary cutting mechanism 64, 65 not being adapted to sever the yarn 12 when it is withdrawn from feeding relation with respect to the needles as at the completion of high splice or double sole knitting, and not being adapted to sever any of the other main yarns when they are withdrawn from feeding relation with respect to the needles.

It will be noted by inspection of Figs. 8-12 inclusive that the plate 27 is in such a position as to separate the high splice or other yarns 12 from the wrap stripe threads 13, 13', the threads passing through a recess 27' in the plate and then beneath the plate so as not to become entangled in the clamping mechanism and/or be severed by the cutting mechanism 64, 65.

Although in the foregoing description the parts and combinations thereof have been referred to in specific terms, it is not the intention to limit the invention otherwise than as required by the recitations in the claims themselves.

I claim:

1. A circular knitting machine having a rotary needle bed and means for feeding yarns to the needles including one yarn to be knitted by less than all the needles and during the knitting of a plurality of courses, a movable guide for presenting and withdrawing the yarn last mentioned to the needles, mechanism for severing the said yarn during the knitting of each course including connections between the yarn guide and severing element so that when the yarn guide is moved to feeding position the yarn severing mechanism is acted upon to effect the severing of the yarn.

2. In a knitting machine, a yarn feeder, mechanism for moving said feeder into and out of yarn-feeding position, a yarn cutting device, means directly controlled by said feeder for actuating said device to cut the yarn, the actuation of the device being effected by movement of the feeder to yarn feeding position.

3. In a knitting machine of the circular, independent needle type, needles and movable yarn guides for feeding desired yarns thereto; means adapted to act to clamp and sever yarns interchangeably fed to the needles during the knitting of a stocking; means actuated at least once during each knit course, to sever one of the yarns, the yarn severing means being located substantially diametrically opposite the yarn feeding position, and directly controlled by the movements of one of the yarn guides, to and from feeding positions.

4. In a knitting machine of the circular, independent needle type, needles and movable yarn guides for feeding desired yarns thereto; means adapted to act to clamp and sever yarns interchangeably fed to the needles during the knitting of a stocking; means actuated at least once during each knit course, to sever one of the yarns, and by movement of one of the yarn guides to yarn feeding position.

5. In a circular knitting machine of the independent needle type, needles and yarn guides; means for severing the yarns when they are withdrawn from feeding relation with respect to the needles for one or more complete courses and to clamp and retain the severed yarn ends; one of the yarn guides adapted to feed splicing yarn to certain of the needles only during each course of knitting, the splicing yarn being moved to floating position after the completion of each partial course of knitting; means adapted to sever the yarn floats at one end only thereof at a point adjacent to the last wale having knit therein

the splicing yarn; connections including a two-armed lever, one arm thereof being in constant engagement with the splicing yarn guide, the other arm thereof being positioned adjacent to the yarn severing means for the splicing yarn, the severing means consisting of relatively movable yarn severing members, an element movable therewith and adapted to be engaged by the second mentioned lever arm, the two-armed lever connection between the splicing yarn guide and the splicing yarn severing means causing relative separation of the said yarn severing members upon movement to non-feeding position of the splicing yarn guide, and causing relative movement of the yarn severing members to yarn severing position upon the movement of the splicing yarn guide to active, feeding position.

6. In a circular knitting machine of the independent needle type, needles and yarn guides, one of the said yarn guides adapted to feed a reinforcing yarn to certain of the said needles only, and during the knitting of a number of courses; means acting in cooperation therewith to sever the said reinforcing yarn adjacent to the last wale having knit therein the reinforcing yarn, said means consisting of a lever one arm thereof resting upon the reinforcing yarn guide and movable therewith, the severing means having an element thereon adapted to be engaged by another arm of the said lever to position the severing means to receive the reinforcing yarn when withdrawn from feeding relation with respect to the needles, the severing means thus being positioned to receive the reinforcing yarn by movement of the reinforcing yarn guide to idle, non-feeding position, and moving to sever the said reinforcing yarn when the said guide moves to active, feeding position.

7. In a circular, independent knitting machine, needles and movable yarn guides for feeding yarns thereto, means adapted to clamp and sever yarns interchangeably fed to the needles during the knitting of a stocking, and means actuated at least once during the knitting of each course to sever one of the yarns and by movement of one of the yarn guides to yarn feeding position, there being mechanical connections between the yarn guide and the yarn severing means second mentioned whereby said movement of the said guide to yarn feeding position causes the yarn severing means second mentioned to sever the yarn last mentioned.

8. In a knitting machine of the independent needle, circular type, yarn guides for feeding a main or body yarn as well as a reinforcing yarn to the needles, means for clamping and severing a yarn withdrawn from feeding relation with respect to the needles said means including an element acting at all times to hold one or more of the yarns, and means adapted to sever the high splice and double sole yarn, the parts being so related that said mentioned element will hold the resultant yarn floats until the said yarn is knit in by the needles for the following course.

9. In a knitting machine, yarn guides, certain of the guides adapted interchangeably to feed yarns to the needles, means acting in conjunction therewith to sever the yarns withdrawn from feeding relation with respect to the needles and including an element to clamp the severed ends,

auxiliary means adapted to sever once for each course of knitting yarn knit in for partial courses only, the severing occurring at one end only of the knit in partial courses, the parts being so related that the yarn clamping element will temporarily retain the ends of the yarn cut by the auxiliary severing means.

10. In a knitting machine, yarn guides, certain of the guides adapted interchangeably to feed yarns to the needles, means acting in conjunction therewith to sever the yarns withdrawn from feeding relation with respect to the needles and including an element to clamp the severed ends, and means to sever at least once for each course of knitting yarn knit in for partial courses, the parts being so related that the clamping element will temporarily retain the ends of the yarn cut by the auxiliary severing means.

11. A circular knitting machine having a rotary needle bed and means for feeding yarns to the needles including one yarn to be knitted by less than all the needles and during the knitting of a plurality of courses, a movable guide for presenting and withdrawing the yarn last mentioned to the needles, mechanism for severing the said yarn during the knitting of each course including connections between the yarn guide and severing element so that when the yarn guide is moved the yarn severing mechanism is acted upon to effect the severing of the yarn.

12. In a knitting machine, a yarn feeder, mechanism for moving said feeder into and out of yarn-feeding position, a yarn cutting device, means directly controlled by said feeder for actuating said device to cut the yarn, the actuation of the device being effected after the yarn has been withdrawn from feeding position, by movement of the feeder.

13. A circular knitting machine of the independent needle type having a rotary needle cylinder, means for feeding one or more yarns to the needles, means for severing any of said yarns when withdrawn from feeding relation with respect to the needles after knitting complete circular courses, means for feeding one of said yarns to some only of the needles for partial courses, said severing means not being adapted to sever the partial course yarn during the knitting of partial courses, other yarn severing means adapted to sever the partial course yarn at least once during the knitting of each partial course, said partial course yarn severing means not being adapted to sever the yarns withdrawn after the knitting of complete courses, in combination with means for wrapping one or more threads around selected needles during the knitting of the hereinbefore mentioned partial courses and in such a manner as to provide floats of a wrap thread from course to course on the inner face of the fabric, the hereinbefore mentioned severing of the partial course yarn from course to course avoiding elongation of said wrap thread floats which extend from course to course, and other means for acting upon the wrap thread floats to guide them so that the said floats are maintained below the yarn severing mechanism so as not to foul the same.

AUGUSTIN GAGNE.
